TRENCHING AND CABLE LAYING MACHINE
Arthur G. Schramm, 215 N. 28th St., Phoenix, Ariz.
Filed May 4, 1961, Ser. No. 107,828
6 Claims. (Cl. 61—72.6)

This invention concerns a trenching and cable laying machine.

One of the objects of the invention is to provide a propelled machine which will dig a comparatively narrow ditch and direct a cable into the ditch and then refill the ditch and tamp the dirt down to grade;

Another object of the machine is to provide a means for making the self-propelled portion of the machine easily portable by folding up and elevating certain elements of the refill mechanism;

Still another object is to provide a means for steering the self-propelled portion of the machine either while digging or when in operative folded position;

Another object of the machine is to provide means for supporting the refill mechanism and tamping mechanism when in operation;

Still another object is to provide means to keep unwanted earth, stones and the like from the ditch while the cable is being laid;

Still another object of the invention is to provide an adjustable means for supporting the refill mechanism in a manner so that it will not interfere with the operation of other parts of the machine.

Another object of the invention is to provide a means for adding moisture to the removed dirt, before refilling for more effective compaction.

Other objects will appear hereinafter.

I attain the foregoing object by means of the devices, parts and combinations of parts shown in the accompanying drawings, wherein:

FIGURE 1 is a plan view of the machine in operating position;

FIGURE 2 is a side elevational view of the machine in a similar position;

FIGURE 3 is a side elevational view of the cable laying portion of the machine;

FIGURE 4 is a front elevational view of the cable laying portion of the machine as shown in FIGURE 3;

FIGURE 5 is a side elevational view of one of the tamping and refill wheel supports, drawn on a somewhat enlarged scale and with portions broken away to show interior construction;

FIGURE 6 is a side elevational view of the tamping mechanism, as viewed on line 6—6 of FIGURE 1, showing movement of the several parts in dotted outline;

FIGURE 7 is a section taken through the tamping mechanism and drawn on a somewhat enlarged scale;

FIGURE 8 is a plan view of a wheel axle driving mechanism and electrical connections used to connect or disconnect it from the drive shaft;

FIGURE 9 is a plan view of the driving wheels showing means for controlling the electrical brake, also the clutch mechanism shown in FIGURE 8 and showing an earth moistening device used in connection with the operation of the digging mechanism (stinger) previously described.

Similar parts are given similar numbers in the several views.

In FIGURES 1 and 2, which are the assembled views, 2 indicates the frame of the machine in general. 3 indicates an engine or motor used to drive the several parts of the machine. 4 indicates the endless or digging bucket chain portion of the machine. 5 indicates the cable guide tube held by bracket 120A which is attached to stretcher member 32. 6 indicates the rear refilling portion of the

2

machine including the spiral flights 7 which move the dirt from areas on each side of the ditch back to a central position over the ditch. 8 indicates the tamper in general and 9 is a driving mechanism for the tamper.

5 The cable to be laid is marked A and this, as shown in FIGURE 2, extends from a position in front of the machine frame 2 downward and rearward through a cable laying guide tube 12. It will be understood that the trench digger 4 consists of an endless chain belt 14 on which there are numerous buckets or scrapers 15 and that this chain belt is driven by a sprocket 16 indicated by dotted lead line shown in FIGURE 1 and solid lead line shown in FIGURE 2 which is pressed on shaft 17. The ends of shaft 17 are journaled in self-aligning enclosed bearings 18 and 18' which are attached to the side plates 20 and 20' which are a part of the frame 2. These plates are joined by suitable cross members 21 at the front and 22 at the top. Engine 3 is supported on this top plate 22. The engine is provided with a speed reduction gear in an 10 enclosing case 24, and the drive through this mechanism comes out at shaft 25 which may be considered the main drive shaft. A hand operated clutch 10 may be used to connect and disconnect power from motor 3 to the drive mechanism 24. A sprocket 10 on the drive shaft 25 carries a chain 27 which runs over a sprocket 28 on the forward digger supporting shaft 17 which extends between the side plates 20 and 20' of the body 2. This shaft affords support for the digger 4, as well as providing driving means for rotating shaft 17 which operates the buckets of 15 the digger. The digger chain 14 is supported between sprocket 16 on shaft 29, at the front, and a lower sprocket 30 at the rear. These sprockets are supported on bearings 31 and 31' which are joined by a stretcher member 32 and made adjustable by screw means 33. A clutch 20 35 is provided on shaft 25 to connect or disconnect operation movement of the digger chain.

From the foregoing it will be understood that the digger is pivotally supported at the forward end and adapted to movement upward out of the ditch B, as indicated by the arrow 34. Since the movement of the machine is from left to right, as viewed in FIGURE 2, it will be readily apparent that the earth C is dug and removed as the machine advances and that the earth is brought up to the surface by the digging buckets on the lower run 14c of the chain 14, forward flights 19 and 19' are spiral and pitched to carry the dirt from the edges of the ditch outward.

The cable A is fed through the tube or pipe 5 exits at A-2 near the rear of the machine and is kept from chafing or damage by rollers 12a near both ends of the tube.

Above the rear of this tube there is a vertical scraper baffle 40. This is made of pliant flexible material such as comparatively stiff rubber belting and is made wide enough to extend across the width of the ditch B, and then have an excess width. This arrangement cramps the baffle somewhat and causes it to operate with an arcuate curve whereby its lateral edges slide along the inner faces of the ditch. This baffle prevents loose dirt from the back-fill from entering the ditch ahead of the cable guide 12. Otherwise, earth from the back-fill would enter the ditch before it should. A small spring steel scraper baffle 43 is attached to the under part of tube 12 and acts as a baffle or an earth guide to force loose earth forward and clean the bottom of the ditch at position 44. This keeps loose earth from falling back into and partially filling that portion of the ditch where the cable is being laid. This scraper may be known as a ditch bottom baffle scraper.

At the rear end of the body plates 20 and 20' there are pivot shafts 50 and 50'. Shaft 50 is live and is

used to drive the rear flight or spiral scraper 52 on shaft 53. This shaft is driven by chain 54 from sprocket 55 on shaft 50. Shaft 50 is, in turn, driven by chain 56 from sprocket 57 on the digger shaft 29. A clutch 58 is provided at the left end of shaft 29 to connect and disconnect sprocket 57 and thereby disconnect or operate the rear flight 52, when desired, independently of the operation of the stinger.

On the inner end of shaft 50 there is a sprocket 60 which drives chain 61 and sprocket 62 on a shaft 63 which is journaled in a U-shaped subframe 65. On shaft 63 there is an unbalanced weight 66 which provides vibration for the back-fill tamper 8 carried on the rear of subframe 65. It is to be understood that U-shaped frame 65 is pivotally supported on shafts 50 and 50' and the tamper 8 and its shaft 63 may therefore be varied vertically, or swing out of ditch B.

Tamper 8 is made of a plate 68 which is comparatively narrow but has a strip of metal 69 attached to its rear and bottom edges. This aids in tamping by providing a wider face which will contact the earth.

At the rear end of the U-shaped frame D there are two riding wheels 70 and 70' supported by springs 71 in tubular housings 72. The wheels are journaled in sliding members 73 which operate slidably up and down within the tubular supports 72. Tension of the springs 71 is adjustably maintained by screws 74 which have cranks 75 at their top ends. In this way the riding wheels 70 and 70' are resiliently maintained in position and at the right height to carry the weight of the U-shaped frame D and the attached parts above mentioned.

Propulsion of the device is provided by power take-off chain 100 which runs over a sprocket 101 on shaft 25. A suitable clutch 102 cuts in or cuts out power from the forward sprocket 101 on shaft 25 so that the propulsion means may be run independently of the digger operation. From chain 100 the power is transmitted to the transmission shaft 100a which provides power for transmission gear box E. This box drives shaft 103 by means of sprocket 212 and chain 213. Shaft 103 drives both front or forward wheels 104 and 104'. The front or forward wheel hubs 105 and 105' are provided with sprockets which drive sprockets 106 and 106' on the rear wheels 107 and 107', through chains 108 and 108'.

Steering may be accomplished by slowing down or stopping the drive wheels on one side of body 2 and/or speeding up the drive wheels on the opposite side. This is similar to the way in which caterpillar tractor treads are operated. The details of this drive and brake and control of the right and left wheels, respectively, are shown in FIGURES 8 and 9.

Each of the forward wheels 104 and 104' is provided with a hub plate 200 which has a flange 201 connected to a clutch housing drum 202. This drum contains clutch shoes 203 of the internal expansion type which are operated by electrical mechanism including a ring magnet 204.

In FIGURE 8 note that the sprocket teeth 211 which drive the chains that run over the sprocket on the housing on forward wheels are on the outside of the housing drums 202.

Ring magnet 204, as shown in FIGURE 8, is connected in circuit from ground on the axle 103 to a live conductor 205 which extends through an insulating ring 206 on axle 103. Conductor 205 is brought out to a contact ring 207 on ring 206. This ring is contacted by a brush 208 contained within an insulating case 209 and the brush is electrically connected to a conductor 210 which leads to the switches 220, necessary for its operation.

Tube axle 103 carries a driving sprocket 212 which is connected by a drive chain 213 and transmission gear box E to the engine 3. The axle is journaled in bearing 214 so that it is supported on frame side plate 20. It is to be noted that axle 103 is hollow and that the wheel hub

200 and the brake drum 202 are connected to a stub shaft 216 which is journaled on ball bearings 217 and 218 within tubular axle 103. Thus, the wheel 104, or its right hand counter part, may be disconnected from the drive torque of axle tube shaft 103 by releasing the shoes 203a.

Wheels 107 and 107' have hubs and drums the same as 104 and 104' except that their hubs are solid with the wheels and the brake shoes and mounting plates 240 and 240' are solid with stationary stud axles 241 and 241'.

In FIGURE 9 the front drive wheels 104 and 104' are shown, together with portions of the frame 2, to illustrate the parts upon which the electrical features operate, thus an ordinary electrically operated brake 230 may be applied to the rearward wheels 107 and 107' to brake either side of the body through conductors 231 and 231' and the switches shown at 220 and 220'. Whereas, the axle 103 may be operatively connected to wheels 104 and 104' through the conductors 210 and 210' and through the switches 220 and 220', as desired. Although the drawing shows the details of this structure only on the left hand side for wheels 104 and 107 it is to be understood that the right hand counter part of this structure is the same. Electrical energy to operate the solenoids within the wheels 104 and 104' as well as brakes 230 and 230' is furnished from a battery 221 and controlled through a master switch 222.

In FIGURE 9 there is also shown a water supply pipe 300 which has a valve 301 connected through a T 302 to two spray pipes 303 and 303'. Spray nozzles 304 and 304' are positioned and directed downwardly at the ends of these spray pipes. Pipe 300 is connected to any convenient source of water supply which is movable with the body of the device here concerned and the spray of water can be directed on the earth as it bubbles upward from the stinger 4. This helps settle the earth when it is refilled into the trench after the flights 52 have moved it centrally into the trench.

When it is necessary to move the entire machine the stinger 4 may be pivoted on its drive shaft 29 and swung up and out of the ditch forwardly. This is accomplished by operating screw 235 which threads in a pivoted nut 236 and has its lower end attached to an offset pivot 237 which is eccentrically positioned relative to the stinger drive shaft.

When the machine is not operated and the stinger is moved out of the ditch B the supports for the refilling mechanism and tamper may be removed from the ditch by folding up the U-shaped frame D and the parts attached to it. The frame may optionally be removed by disconnecting shafts 50 and 50'.

Likewise, the U-shaped frame 66 may be removed when desired and the tamper and its attached mechanism removed or folded out of the way.

Mechanism for the wheel drums to set and release the brakes which operate on the drums as shown in patents, for example, to Oetzel, No. 2,407,510 and 2,510,959; also the patent to Titus, No. 2,541,445 and Yost No. 2,426,135. These patents show the mechanism of the type herein concerned and have an earlier date than the filing date of the instant application.

I claim:

1. A trench and cable laying machine composed of a frame including two parallel laterally positioned and transversely separated upright side plate members, having connecting transverse top and front plates, said frame having front and rear, wheels mounted on transverse shafts on said frame in tandem arrangement on each side thereof, the transverse shaft to which the forward wheels are attached extending through said frame and having means for receiving driving motion; an engine mounted on said frame and attached through clutch means to said wheels; a transverse power-driven shaft journaled at its ends in said frame plate members; an endless chain digger operated by said transverse power-driven shaft, a cable

positioning tube pivotally attached to said transverse power-driven shaft at its forward end and adapted to receive a cable to be laid in a trench formed by said digger, said tube extending downwardly and rearwardly from said frame, rollers at the rear of said tube to minimize friction of a cable extending and running through said tube, a curved pliant baffle at the rear of said tube extending upwardly and laterally spanning the transverse width of said digger; having its edges pliantly bearing on the walls of said trench, a vibrating tamper positioned adjacent to and rearwardly of said baffle attached to a U-shaped frame, said U-shaped frame pivotally attached to the rear ends of said frame plate members and supporting said tamper, mechanical means on said U-shaped frame for vibrating said tamper a second U-shaped frame positioned outwardly of said first mentioned U-shaped frame and pivotally attached to said plate members, riding wheels vertically adjustable attached to the rear of said second U-shaped frame to support the weight of the rear of said second U-shaped frame, mechanism for driving said digger from said engine on said frame and mechanism for driving the tandem wheels on each side of said frame; said mechanism operable to drive either of the right or left forward wheels, as desired, and a rotary spiral scraper operating in the rear end of said second U-shaped frame having right and left spiral flights disposed on a transverse shaft in said frame and adapted to move dirt from each side of said ditch centrally and into said ditch.

2. The mechanism described in claim 1 wherein the bottom of the cable positioning tube is combined with a forwardly curved scraper for scraping rocks and loose dirt from the space in front of the cable positioning tube.

3. The mechanism described in claim 1 in combination with a water pipe attached to said frame having nozzles directed downwardly toward the top of said power driven digger.

4. A trench and cable laying machine composed of a frame including two parallel laterally positioned and transversely separated plate members, and transverse top and front plates, said frame having a front part and a rear part, wheels mounted on transverse shafts on said frame in tandem arrangement on each side thereof, the transverse shaft to which the forward wheels are attached extending through said frame and having means for receiving driving motion; an engine mounted on said frame and attached through clutch means to said wheels; a transverse digger shaft journaled at its ends in said frame plates; an endless chain power driven digger operated by said transverse shaft, a cable positioning tube adapted to receive a cable to be laid in a trench formed by said power driven digger, said tube extending downwardly and rearwardly from a place of attachment on said body frame, rollers at the rear of said tube to minimize friction of a cable extending and running through said tube, a curved baffle of pliant material at the rear of said tube extending upwardly and having its edges pliantly bearing on the walls of said trench, mechanism for driving said digger from said engine on said frame and mechanism for driving the tandem wheels on each side of said frame; said mechanism being operable to drive either of the right or left forward wheels, as desired, a U-shaped frame having right and left spiral flights disposed on a transverse shaft in the first mentioned frame and adapted to move dirt from each side of said ditch centrally and into said ditch.

5. A trench and cable laying machine composed of a body frame including two parallel laterally positioned and transversely separated plate members, and transverse top and front plates, said frame having a front part and a rear part, wheels mounted on transverse shafts on said

frame in tandem arrangement on each side thereof, the transverse shaft to which the forward wheels are attached extending through said frame and having means for receiving driving motion; an engine mounted on said frame and attached through clutch means to said wheels; a transverse digger shaft journaled at its ends in said frame plates; an endless chain digger stinger operated by said transverse shaft, a cable positioning tube adapted to receive a cable to be laid in a trench formed by said digger, said tube extending downwardly and rearwardly from a place of attachment on said body frame, rollers at the rear of said tube to minimize friction of a cable extending and running through said tube, a curved baffle at the rear of said tube extending upwardly and having its edges disposed to pliantly bear on the walls of said trench, mechanism for driving said digger from said engine on said frame and mechanism for driving the tandem wheels on each side of said frame; said mechanism being adapted to drive either of the right or left forward wheels, as desired, and brake mechanism selectively operable on the rear tandem wheels and electrical operating mechanism therefor including selective switches adapted to operate the brakes and clutches for either of the oppositely disposed rear wheels.

6. A trench and cable laying machine composed of a frame including two parallel laterally positioned and transversely separated plate members, and transverse top and front plates, said frame having a front part and a rear part, wheels mounted on transverse shafts on said frame in tandem arrangement on each side thereof, the transverse shaft to which the forward wheels are attached extending through said frame and having means for receiving driving motion; an engine mounted on said frame and attached through clutch means to said wheels; a transverse digger shaft journaled at its ends in said frame plates; a continuous chain digger operated by said transverse shaft, a cable positioning tube adapted to receive a cable to be laid in a trench formed by said digger, said tube extending downwardly and rearwardly from a place of attachment on said body frame, mechanism for driving said digger from said engine on said frame including a clutch for disconnecting said drive when desired and mechanism for driving the forward wheels of said tandem laterally positioned wheels including an electro-magnetic clutch contained within the wheels and operated by electrical means on the frame of said machine to connect and disconnect the electro-magnetic clutch means to a source of electricity; said mechanism being adapted to selectively drive and operate either of the right or left forward laterally positioned wheels as desired, and electro-magnetic brake mechanism in the rear tandem wheels independently operated by electrical switches from a source of energizing electric current disposed in the body of said machine.
